(57) **CLAIM**

The ornamental design for a vibrating apparatus, as shown and described.

DESCRIPTION

FIG. 1 is a perspective top view of a vibrating apparatus, showing my design;

FIG. 2 is a perspective bottom view of the vibrating apparatus;

FIG. 3 is a top view of the vibrating apparatus;

FIG. 4 is a bottom view of the vibrating apparatus;

FIG. 5 is a first side view of the vibrating apparatus;

FIG. 6 is a second side view, opposite the first side view of FIG. 5, of the vibrating apparatus;

FIG. 7 is a front view of the vibrating apparatus; and,

FIG. 8 is a back view of the vibrating apparatus.

Dotted lines, when present, in the figures form no part of the claimed design.

1 Claim, 6 Drawing Sheets
